UNITED STATES PATENT OFFICE.

FRANK D. SCOTT AND OSCAR L. GORDON, OF SANTA CRUZ; CALIFORNIA.

MANIFOLD WRITING-CASE.

SPECIFICATION forming part of Letters Patent No. 281,403, dated July 17, 1883.

Application filed June 20, 1882. (No model.)

To all whom it may concern:

Be it known that we, FRANK D. SCOTT and OSCAR L. GORDON, of Santa Cruz, county of Santa Cruz, State of California, have invented 5 an Improved Manifold Writing-Case; and we hereby declare the following to be a full, clear, and exact description thereof.

Our invention relates to a novel case or tablet for producing manifold impressions of writing; and it consists in certain details of construction and combinations of devices, as hereinafter fully described and claimed.

The object of our invention is to provide a convenient means for producing manifold impressions for use by clerks and salesmen in 15 stores, or for any uses requiring copies, the advantages of which we will show hereinafter.

Referring to the accompanying drawings, Figure 1 is a perspective view of our invention. Fig. 2 is a longitudinal section. Fig. 3 is a perspective view of a roll of writing-paper. Figs. 4 and 5 are details.

A represents a small box, the lid B of which is shorter than said box, and is hinged to open 25 lengthwise. Its front end, when closed, does not extend to the edge of the box, but leaves a space, a. In the inner side of the rear of the box is pivoted a vertically-swinging plate, C, carrying two spindles or shafts, c, extending from its side, about midway of its depth, across the box, to the other side, into grooves b b, made in that side. The forward upper edge of the plate has extending from it across the box in the opening a, between the lid and 30 box, a tube, d, with a longitudinal slot, d', in its upper side. This plate C is adapted to be raised to a vertical position to free the outer ends of its shafts c and tube d from the other edge of the box, and is also adapted to assume 35 a horizontal position in the box and to allow the lid to close down, in which position nothing is seen of it but the slotted tube d. In the bottom of the box, at its forward end, are secured suitable staples or hooks, e, one upon 40 each side.

D is a rubber or elastic band secured below by the staples, and passing up by the edges of the box and across the end of the lid when said lid is closed down. The band may be 45 drawn off the lid and slipped over the front end of the box when the lid is to be raised.

D' is another elastic band passing below and above the rear top end of box A. The upper part of this band is adapted to be drawn over the edge and slipped around the end of the 55 box when necessary.

E represents a continuous sheet of writing-paper of any length, having printed at suitable intervals over its entire length bill-heads, or whatever description or character of matter is desired. This is made up into a roll, as shown, leaving a central opening. E' represents a similar roll of paper.

F represents a sheet of carbon-paper a little shorter than the box. At one end it has 65 pressed down over its edge a strip or rim of metal, f, Fig. 5. The box being opened, the plate C, with its shafts c and tube d, is raised. The roll of paper E is slipped over the rear shaft and the roll E' is fitted upon the next 70 shaft. The metal rim f of the carbon-paper is slipped into the slotted tube d. The plate C is then lowered into the box. The end of roll E' is drawn forward under tube d, and extends over the edge of the box, between it and the 75 said tube. The paper E is drawn forward over the tube d and carbon-paper, and extends to the edge or end of paper E', both layers of writing-paper being drawn sufficiently beyond the end of the carbon-paper to allow them to be grasped without including the 80 carbon-paper. The lid B is then closed down, and the sheets of writing-paper and intervening carbon-paper are all turned backward over and upon the lid, the former extending beyond the box, while the latter extends to the hinge of the lid, or thereabout. The elastic band D is then slipped from the end of the box across the top of the papers, and the band 85 D' is likewise slipped over the papers at their 90 end, thus securing the lid to the box and the papers to the lid.

Across the top of the back end of the box is secured a cutter, G. This consists of a strip of metal slightly inclined and provided with 95 teeth g.

The use of this device is as follows: We can best illustrate it by reference to the custom of many mercantile establishments, where the salesman, having made a sale, is required to 100 make a memorandum in duplicate or triplicate, as the case may be. One he may keep

himself. The other is sent to the cashier or is given to the customer.

The box is convenient to carry and furnishes a good surface upon which to write. 5 The layers of paper are always in position and the carbon-paper need never be handled. When a memorandum is made, the ends of the writing-papers are grasped and drawn out under the bands until they reach a point where the 10 cutter will sever them below the writing. They are then torn off against the cutter with ease and precision. There is no trouble in drawing the sheets out, as they pass off the rolls within the box without interference. The carbon-paper remains in position until worn out, 15 when a new sheet with a metal rim may be readily inserted in the tube *d*. When the rolls of paper are exhausted, new rolls readily prepared may be placed upon the spindles *c*. 20 For this purpose we have prepared these rolls of paper of the width of the box, and have printed at suitable intervals over the length of paper a bill-head or any matter of similar character to designate and distinguish the 25 memorandum-slips. These rolls may be kept in stock, and their ends are pasted down or otherwise secured to prevent them from unrolling when not within the box.

Having thus described our invention, what we claim as new, and desire to secure by Letters 30 Patent, is—

1. The manifold writing-case herein described, consisting of the box *A*, having lid *B*, extending nearly its entire length, though leaving opening *a* in front, interior pivoted side 35 *C*, paper rolls *EE'*, reproducing-paper *F*, elastic bands *D D*, and knife *G*, all arranged to operate as set forth.

2. The combination of the pivoted side *C*, moving in a vertical plane and provided with 40 holes *c*, with the shafts *c* and grooves *b*, as described.

3. The combination of the cylinder or tube *d*, having longitudinal slot *d'*, and situated in opening *a*, with writing-paper passing each 45 side of it, with the reproducing-paper *F*, clipped at the forward end in the strip *f*, which is slipped into the slotted tube *d*, as described.

In witness whereof we hereunto set our hands.

FRANK D. SCOTT.
OSCAR L. GORDON.
